UNITED STATES PATENT OFFICE

99,090

DESIGN FOR A COMBINED CLOCK, HYGROMETER, AND THERMOMETER

Gustavus C. Kuehn, Detroit, Mich.

Application November 2, 1935, Serial No. 59,349

Term of patent 7 years

To all whom it may concern:

Be it known that I, Gustavus C. Kuehn, a citizen of the United States, residing at Detroit, in the county of Wayne and State of Michigan, have invented a new, original, and ornamental Design for a Combined Clock, Hygrometer, and Thermometer, of which the following is a specification, reference being had to the accompanying drawing, forming a part thereof, in which,

Figure 1 is a front elevational view of the combined clock, hygrometer and thermometer show-

ing my design, A designating a thermometer, B a clock, and C a hygrometer.

Figure 2 is a plan view.

Figure 3 is an end elevational view, and

Figure 4 is a transverse sectional view taken on line 4—4 of Figure 1.

I claim:

The ornamental design for a combined clock, hygrometer, and thermometer, as shown and described.

GUSTAVUS C. KUEHN.
